SOFA BED HINGE

Harry Raginsky, Montreal, Quebec, Canada, assignor to Progress Spring Bed Limited, Montreal, Quebec, Canada

Application December 10, 1948, Serial No. 64,513

7 Claims. (Cl. 5—57)

1

This invention relates to improvements in sofa beds of the type in which the seat and back sections are fastened together at their ends by locking and releasing hinge connections which are also connected to end members of the sofa bed frame and support the seat and back sections for swinging movement from a sofa-forming position to a bed-forming position and vice versa, the seat and back hinge members of each hinge connection being provided with complementary locking devices which serve to lock the seat and back sections against relative movement in their sofa-forming positions but permit the seat section to be moved relatively to the back section to a horizontal bed-forming position after the seat and back sections have been moved as a unit to an intermediate hinge unlocking position in which the back section is disposed in a horizontal bed-forming position with the seat section in a substantially vertical position.

The primary object of the present invention is to provide improved hinge connections of the type referred to which are simpler in design and cheaper to manufacture and install than the hinge connections heretofore employed for supporting the seat and back sections for movement from a sofa-forming position to a bed-forming position and vice versa.

Other objects, advantages and characteristic features of the invention will be more readily understood from the following detailed description taken in connection with the accompanying drawings, in which—

Fig. 1 is a side elevational view of one of my improved hinge connections as it appears looking toward the inner side. In this view the seat and back members fastened together by the hinge connection are shown in cross section together with one of the end members of the sofa bed frame to which the hinge connection is also fastened, the hinge connection and the seat and back sections of the sofa bed being shown in their sofa-forming position.

Fig. 2 is a view similar to Fig. 1 but showing the seat and back sections transposed to a position in which the back section is disposed in a horizontal bed-forming position while the seat section is disposed in a vertical position.

Fig. 3 is a view similar to Fig. 2 but illustrating the manner in which the seat section is movable from the vertical position shown in Fig. 2 to an inclined hinge unlocking position to permit subsequent independent movement of the seat section to a bed-forming position in horizontal alignment with the back section.

2

Fig. 4 is a view showing the seat and back sections in their horizontally aligned bed-forming position.

Fig. 5 is an inside elevation of the hinge connection per se as it appears in the absence of the latch actuating plate and control bars shown in the preceding figures.

Fig. 6 is a plan view of the latch actuating plate shown in Figs. 1 to 4 inclusive.

Fig. 7 is a sectional view taken substantially along the section line 7—7 of Fig. 1.

In these drawings my improved hinge connection is designated in its entirety by reference numeral 4. It comprises a back hinge member 5 having one end fastened to the back section 6 of the sofa bed and a seat hinge member 7 having one end fastened to the seat section 8 of the sofa bed. The remaining ends of the hinge members 5 and 7 are pivotally secured together in overlapping relation by a pivot bolt 9 having a head 10 at one end and a clamping nut 11 at the opposite end.

The hinge members 5 and 7 are supported on an end member 12 of the sofa bed by control bars 13 and 14 and control bar supporting plate 15. The upper end of control bar 13 is fastened to the hinge 4 by the pivot bolt 9 and is interposed between the head 10 of the bolt and a washer 16 engaging the outer side of the pivotally connected end of hinge member 7 as shown to advantage in Fig. 7. The lower portion of control bar 13 is intermediately pivoted at 17 to supporting plate 15 which is suitably fastened to the end member 12. The upper end of control bar 14 is secured by a pivot 18 to the back hinge member 5 and has its lower portion intermediately pivoted at 19 to supporting plate 15. The lower ends of control bars 13 and 14 which extend below the pivots 17 and 19 are connected together by a coiled tension spring 21.

A hinge locking latch 23 is intermediately pivoted to the inner side of the back hinge member 5 by a suitable pivot connection 24 which is located below the pivot bolt 9 and at a point between the pivot bolt and that end of the hinge member 5 which is connected to back section 6. It will also be noted that the latch pivot 24 is located relatively close to the end of the latch nearest back section 6 and that this end of the latch is provided with a notch 25 receiving therein one end of a bowed spring 26. The other end of latch spring 26 is engaged in a hole 27 provided in hinge member 5. The end of latch 23 remote from back section 6 is provided with a recess 29 in which a locking stud 30, carried by

the seat hinge 7, is engaged when the component parts of the sofa bed and the hinge are disposed in the sofa bed-forming position shown in Fig. 1 or the intermediate position shown in Fig. 2. In these positions of the sofa bed the line of action of spring 26 against latch 23 is substantially as indicated by the arrow Z in Fig. 2 and tends to hold the latch engaged with the locking stud 30.

The hinge member 5 also carries a latch engaging stop pin 31 which underlies the latch between the latch pivot 24 and the latch recess 29 and serves to limit swinging movement of the latch in one direction when it is released from the locking stud 30.

The latch 23 and its spring 26 lie between the inner side of the hinge member 5 and a covering plate 33 which is removably secured in place so that it forms a fixed part of hinge member 7. In this connection it will be noted that the stud 30 and a companion stud 34 also carried by hinge member 7 are provided with reduced outer ends which are fitted in openings 35 and 36 provided in plate 33. It will also be noted that plate 33 is provided with an opening 37 (Fig. 7) through which the shank of the pivot bolt 10 extends, there being a washer 38 arranged on the bolt 9 between plate 33 and hinge member 5 and a second washer 39 arranged on the bolt between plate 33 and clamping nut 11. It will thus be seen that, while plate 33 is pivotally mounted on bolt 10, it is held against motion relative to hinge member 7 by the studs 30 and 34 having their reduced outer ends engaged in the plate openings 35 and 36. Plate 33 also carries a latch releasing stud 40 projecting inwardly therefrom toward hinge member 5 and positioned to engage the upper edge of that portion of latch 23 which extends from latch pivot 24 toward seat section 6.

In the sofa forming position of the sofa bed described herein the seat and back sections 6 and 8 and the component parts of hinge connection 4 are arranged as shown in Fig. 1, the back section being disposed in a substantially vertical position and the seat section 8 in a position slightly inclined from the horizontal.

When it is desired to transpose the seat section 8 and the back section 6 to a bed-forming position this is accomplished by first swinging the seat section 8 upwardly from the position shown in Fig. 1 to the vertical position shown in Fig. 2. During this movement of seat section 8 the hinge members 5 and 7 are locked together by latch 23 and stud 30 so that they swing as a unit about pivot bolt 10 until back section 6 is disposed in the horizontal position shown in Fig. 2 with seat section 8 disposed in a vertical position. During this unitary movement of seat section 8 and back section 6 about pivot bolt 10 the control bars 13 and 14 swing about the pivots connecting them to hinge members 5 and 7 and supporting plate 15 to take up the position shown in Fig. 2.

When seat section 8 and back section 6 are positioned as shown in Fig. 2, the seat section 8 is capable of a slight further movement relative to back section 6 in the direction indicated by the arrow X to the latch releasing position shown in Fig. 3. During this movement of seat section 8 to the latch releasing position shown in Fig. 3 the latch releasing stud 40 carried by plate 33 is moved against the underlying portion of latch 23 and serves to swing the latch out of engagement with the locking stud 30 normally engaged in the latch recess 29. In this hinge releasing position of latch 23 the line of action

of spring 26 against the latch is substantially as indicated by the arrow Z' in Fig. 3 and tends to hold the latch away from locking stud 30. The seat member 8 and its hinge member 7 are therefore free to swing about pivot bolt 10 and relatively to hinge member 5 in the direction indicated by arrow X' (Fig. 3) to thereby dispose seat section 8 in a bed-forming position in horizontal alignment with back section 6 as shown to advantage in Fig. 4. During the aforesaid movement of seat section 8 and hinge member 7 from the latch releasing position shown in Fig. 3 to the bed-forming position shown in Fig. 4, the back section 6 and its hinge member 5 remain stationary in the position shown in Figs. 3 and 4.

When seat section 8 is moved downwardly to the bed-forming position shown in Fig. 4, the stud 34 carried by hinge member 7 moves into engagement with the upper end of the back hinge member 5 to prevent further downward movement of seat member 8. During this movement thereof the stud 34 contacts the upper portion of the latch 23 and forces the latter downwardly against the resistance of spring 26 into contact with its underlying stop pin 31 to thereby dispose the latch in a position to re-engage the stud 30 and again lock the hinge members 5 and 7 against relative movement when seat section 8 is again raised to the intermediate position shown in Fig. 2 preparatory to returning the seat and back sections to their original sofa forming position. As the latch 23 is moved against its stop pin 31 by the stud 34 the relationship between the latch and spring 26 is changed so that the line of action of the spring against the latch tends to hold the latch against the stop pin 31.

In other words, when seat section 8 is raised from the bed-forming position shown in Fig. 4 to the intermediate position shown in Fig. 2, the hinge members 5 and 7 are again brought into alignment with each other and locked together by re-engagement of latch 23 with the stud 30. This permits the seat and back sections 8 and 6 to be swung as a unit from the intermediate position shown in Fig. 2 to the sofa-forming position shown in Fig. 1. The spring 21 connecting the lower ends of control bars 13 and 14 serves to counterbalance the weight of seat and back sections 8 and 6 and the component parts of hinge 4 to facilitate swinging of the seat and back sections and the hinge members 5 and 7 from the position shown in Fig. 1 to the position shown in Fig. 2.

Having thus described the nature of my invention and a preferred embodiment thereof, it will be understood that various modifications may be resorted to within the scope and spirit of the appended claims.

I claim:

1. A hinge of the character described comprising a pair of pivotally connected hinge members, a spring biased latch intermediately pivoted to one hinge member and provided with a stud receiving recess at one end and a pair of latch engaging studs carried by the other hinge member, one of said studs constituting a locking stud engageable in the recess of the latch and the other stud constituting a latch releasing stud engageable with a portion of the latch located at the side of the latch pivot remote from said stud receiving recess to swing the latch out of locking engagement with the locking stud in response to a predetermined movement of the stud carrying hinge member.

2. A hinge as set forth in claim 1, including a stop pin fixed to the latch carrying hinge member and engageable with the latch to limit swinging movement thereof in one direction.

3. A hinge as set forth in claim 1, in which the stud carrying member is provided with a further stud engageable with the pivoted end of the latch carrying hinge member to limit relative movement of the hinge members in either direction about their pivotal connection.

4. A hinge as set forth in claim 1, including a plate covering said latch and rigidly secured to the stud carrying hinge member for movement therewith, said plate being pivotally connected to the latch carrying hinge member by the pivotal connection between the two hinge members.

5. A hinge of the character described, comprising a pair of hinge members, a pivot connecting said hinge members, a plate rotatably mounted on said pivot, a pair of studs carried by one of the hinge members and fitted in openings in said plate to hold said plate against movement about said pivot independently of the stud carrying hinge member, a latch member intermediately pivoted to the other hinge member and positioned between the said other hinge member and said plate, one end of said latch being formed with stud receiving recesses in which one of said studs is engageable to lock the hinge members together for unitary movement, the other of said studs constituting a stop engageable with the pivoted end of the latch carrying hinge member to limit relative movement of said hinge member in either direction about said pivot when the latch is shifted to a hinge releasing position, a spring connected to the latch and to the latch carrying hinge member and urging the latch to a hinge locking position, and a latch releasing stud carried by said plate and movable into latch releasing engagement with a portion of the latch located at the side of the latch pivot remote from the stud receiving recess of the latch.

6. A hinge, as set forth in claim 5, including a

latch engaging stop pin fixed to the latch carrying hinge member and engageable with the latch to limit swinging movement thereof in one direction.

5 7. A hinge of the character described, comprising a supporting member, a pair of hinge members, a pivot pivotally connecting said hinge members, a control bar pivoted to said supporting plate and having one end pivotally secured to the hinge members by the pivot connecting said hinge members, a second control bar pivoted to said supporting plate and having one end pivoted to one of the hinge members at a point spaced from the pivot connecting said hinge members, a spring biased latch intermediately pivoted to one of the hinge members and provided with a recess at one end for engagement with a locking stud carried by the other hinge member, a latch releasing stud carried by the last mentioned hinge member and engageable with the latch at the side of the latch pivot remote from the latch recess to swing the latch to a hinge releasing position in response to a predetermined relative arrangement of said hinge members, and a spring 10 acting against said control bars and normally tending to swing them about their pivotal connections to the supporting plate.
